UNITED STATES PATENT OFFICE.

HERBERT H. HEWITT, OF BUFFALO, NEW YORK.

CAR-TRUCK.

1,072,721.

Specification of Letters Patent.

Patented Sept. 9, 1913.

Application filed September 5, 1911. Serial No. 647,562.

To all whom it may concern:

Be it known that I, HERBERT H. HEWITT, a citizen of the United States, and a resident of Buffalo, county of Erie, State of New York, have invented certain new and useful Improvements in Car-Trucks, of which I do declare the following to be a full, clear, and exact description:

The invention relates to passenger car trucks and seeks to provide an improved arrangement for mounting the wheel axles therein by which the wheel axles are free to rock in vertical, transverse planes without straining or distorting the parts of the truck or the bearing for the car axle journals.

The invention consists in the improvement hereinafter set forth, illustrated in the accompanying drawings and more particularly pointed out in the appended claims.

Figure 1 is a plan view of a half portion of the improved truck with parts shown in section on the line 1—1 of Fig. 2. Fig. 3 is an enlarged vertical section on the lines 3—3 of Figs. 1 and 2. Fig. 4 is a vertical section on the line 4—4 of Fig. 3. Fig. 5 is a partial elevation of a modification. Fig. 6 is a section on line 6—6 of Fig. 7, and Fig. 7 is a section on line 7—7 of Fig. 5. The truck frame is of usual construction and comprises side beams 10 connected by the end beams 11 and intermediate their ends, by the beams 12 and transoms 13. Links 14 depending from the transoms 13 carry the spring plank 15. The car bolster 16 is arranged between the transoms 13 and is supported by the elliptical springs 17 which in turn rest upon the plank 15. The bolster is provided with the usual center and side bearings 18 and 19. Pedestals 21 are connected to and depend from the side beams 10. The lower ends of the pedestals 21 are connected together and to the end beams 11 by the usual spanner bars 22. The truck frame is supported from equalizer bars 23 through the medium of the equalizer springs 24 and the equalizer bars are carried by the wheel axles.

The parts thus far described may be of any usual or suitable construction.

The wheel axles 25 are provided with wheels 26 fixed thereto and with projecting journals 27 at their ends. These journals are preferably of uniform diameter throughout. The journal boxes are mounted to oscillate in vertically movable sup-

ports on the truck and preferably comprise annular spherical body portions 28 having transverse cylindrical chambers therein for receiving the car journals and bearing for the journals. The spherical journal boxes are mounted within correspondingly shaped concave seats formed in supporting or retaining members which are guided to shift vertically in the pedestals 21 of the truck frame. These supporting or retaining members are formed of separate sections that are fitted together and secured upon the spherical journal boxes and the supporting or retaining members are provided with suitable portions for engaging guide-ways in the truck pedestals 21. As shown in Figs. 1, 2, 3 and 4, the supporting or retaining members comprise rectangular front and rear sections or blocks 29 which are divided upon a vertical plane extending centrally through the spherical journal box and at right angles to the axis of the journal. The retaining members or sections 29 are connected together at the corners by through bolts 30 and are provided with openings through which the journal box extends and with an annular, concave spherical seat within which the box is fitted and within which it is free to move universally. The supporting or retaining members or keepers 29 are provided with projecting portions 31 at their side edges for engaging the vertical guide-ways of the truck pedestals 21. The upwardly extending ends of the equalizer bars 23 extend over and rest upon the supporting members or blocks 29. As the truck passes over irregularities in the track, the supporting members 29 shift vertically within the pedestal 21 and the universal mounting of the journal boxes in the supporting members permits the free rocking movement of the wheel axles without throwing any strain upon the parts of the truck or the bearings for the journals. The wear upon the parts and upon the bearings is thus reduced and there is no danger that the bearings will wear unevenly or be displaced.

The journal boxes are provided with suitable bearings for the journals. Each of these bearings preferably comprises a series of rollers 32 interposed between the journal and the journal box, the latter having an annular raceway for the rollers with a shoulder 33 which engages the outer ends of the rollers. Relatively small spacing rollers 34

are preferably interposed between the bearing rollers. An annular, axially yielding guard 35 is mounted on the journal and engages the inner ends of the journal box and 5 of the rollers to hold the latter in place. This guard is formed of a coiled strip of 10 spring steel. Beyond the shoulder 33 the journal box is provided with a hollow projecting portion 36 having an opening there- 15 in normally closed by a plug 37. This hollow projecting portion is adapted to receive lubricant and supply the same to the surfaces of the bearings. The free movement of the spherical journal boxes within the 20 correspondingly shaped seats of the supporting members accurately maintains the bearing rollers in proper engagement with the cylindrical surfaces between which they are interposed and prevents the wearing, 25 displacement and breaking of the rollers due to the great shock and strain brought upon the parts as the truck passes over irregularities of the track.

In the form shown in Figs. 5, 6 and 7, the 25 supporting members for each journal box, comprise rings or keepers 38 which are screw-threaded into a guide block 39, the latter having an internally threaded bore or opening to receive the rings or keepers 38 30 and the rings or keepers having inner concave spherical faces forming a seat for the journal box. The block 39 fits between the pedestals 21 of the truck and is provided with projecting guide flanges 40 overlap- 35 ping the same. The end of the adjacent equalizer bar 23 is supported on the guide block 39. The rings or keepers 38 are provided with flanges 41 which overlap the outer and inner faces of the guide block 39 40 and are also provided with holes 42 to receive a spanner or like tool. This form in some respects is preferable to the form shown in Figs. 1 to 4, inclusive, since the journal box may be more readily removed 45 for repairs or the like by first removing the outer ring or keeper 38.

It is obvious that the details set forth may be varied without departure from the essentials of the invention as defined in the 50 claims.

I claim as my invention:—

1. In a car truck, the combination with the truck frame and pedestals, wheels and wheel axles, of journal boxes, bearings 55 mounted in said boxes for the journals of said wheel axles, and retaining members guided to shift vertically in the truck pedestals and held against lateral movement and wherein said journal boxes are movably mounted in a manner permitting the free transverse rocking movement of said wheel axles.

2. In a car truck, the combination with the truck frame and wheel axles, of closed 60 journal boxes, bearings mounted in said

boxes for the journals of said wheel axles, and retaining members guided to shift vertically in the truck frame and wherein said journal boxes are free to shift universally.

3. In a car truck, the combination with the truck frame and wheel axles, of journal boxes for said wheel axles having spherical body portions, and retaining members vertically guided and held against lateral movement on the truck frame and having 75 correspondingly shaped seats wherein said journal boxes are movably mounted.

4. In a car truck, the combination with the truck frame and pedestals, wheels and wheel axles having projecting end journals, 80 closed journal boxes having annular spherical body portions, bearings for said journals mounted in said boxes, blocks guided in said pedestals and retaining members or keepers for said journal boxes removably mounted 85 in said blocks and having correspondingly shaped concave seats wherein said journal boxes are movably mounted.

5. In a car truck, the combination with the truck frame, equalizer bars and springs, 90 wheels and wheel axles, of boxes for receiving the journals of said axles, and supporting members for said equalizer bars vertically guided and held against lateral movement on said truck frame and wherein said 95 journal boxes are movably mounted to permit the free transverse rocking movement of said wheel axles.

6. In a car truck, the combination with the truck frame and pedestals, equalizer bars 100 and springs, wheel and wheel axles having projecting end journals, of closed journal boxes having spherical body portions, bearings for said journals mounted in said boxes, and supporting members for said equalizer 105 bars vertically guided in said pedestals and having spherical concave seats wherein said journal boxes are universally movable.

7. In a car truck, the combination with the truck frame and wheel axles, of journal boxes for said wheel axles having annular spherical body portions, and retaining members vertically guided and held against lateral movement on the truck frame and having spherical concave seats for said journal 115 boxes, each of said retaining members comprising connected sections.

8. In a car truck, the combination with the truck frame and pedestals, wheels and wheel axles having projecting end journals, 120 closed journal boxes having annular spherical body portions, bearings for said journals mounted in said boxes, and supporting blocks or keepers vertically guided in said pedestals and having spherical concave seats 125 for said journal boxes, each of said keepers comprising two connected sections.

9. In a car truck, the combination with the truck frame and pedestals, equalizer bars and springs, wheels and wheel axles having 130

projecting end journals, of closed journal boxes having annular spherical body portions, bearings for said journals mounted in said boxes, supporting blocks for said 5 equalizer bars vertically guided and held against lateral movement in said pedestals and comprising connected sections having spherical concave seats wherein said journal boxes are universally movable and free to 10 creep.

10. In a car truck the combination with a truck frame and pedestals, wheels and wheel axles having projecting end journals, of bearing boxes for said journals, supporting blocks vertically guided and held against lateral movement in said pedestals and wherein said journal boxes are movably mounted to permit the free transverse rocking movement of said wheel axles, and 15 springs interposed between said supporting blocks and the truck frame.

11. In a car truck, the combination with the wheels and wheel axles having projecting end journals, of journal boxes for receiving said end journals, and bearing rollers interposed between said journals and said boxes, said truck having vertically movable supports whereon said boxes are movably mounted to permit the free transverse 25 rocking movement of said wheel axles.

12. A car truck provided with two or more wheel axles having projecting end journals and boxes having bearing rollers for said journals, the boxes at the opposite ends 35 of each axle being mounted on the truck to shift independently in vertical direction and to oscillate with the axle, whereby said axles are free to rock independently in transverse direction in passing over irregularities in the track, while said bearing rollers are at all times maintained in proper axial 40 alignment with said axle journals.

13. In a car truck, the combination with the wheels and wheel axles having projecting end journals, of journal boxes, bearing 45 rollers interposed between said journals and said boxes, and vertically movable retaining

members or keepers wherein said journal boxes are mounted to shift universally.

14. In a car truck, the combination with 50 the wheels and wheel axles having projecting end journals, of journal boxes having spherical body portions, bearing rollers interposed between said journals and said boxes, and vertically movable supporting 55 and retaining members having spherical concave seats wherein said boxes are mounted to shift universally.

15. In a car truck, the combination with the truck frame and pedestals, wheels and 60 wheel axles having projecting end journals, of journal boxes having spherical body portions, bearing rollers interposed between said journals and said boxes, and supporting members or keepers vertically guided in 65 said pedestals and having spherical concave seats wherein said journal boxes are free to shift universally.

16. In a car truck, the combination with the truck frame, and wheel axles having projecting end journals, of bearing boxes for 70 said journals having annular spherical body portions and closed, hollow outer ends for receiving lubricant, and supporting members or keepers vertically guided in the truck 75 frame and having spherical concave seats wherein said journal boxes are movably mounted.

17. In a car truck, the combination with the truck frame and pedestals, equalizer 80 bars and springs, wheels and wheel axles having projecting end journals, of supporting blocks vertically guided and held against lateral movement in said pedestals and wherein the ends of said equalizer bars rest, 85 and bearing boxes for said journals movably mounted in said supporting blocks to shift universally and permit the free transverse rocking movement of said wheel axles.
